UNITED STATES PATENT OFFICE.

EMIL R. STASCH, OF CORNING, NEW YORK, ASSIGNOR OF ONE-HALF TO
GEORGE R. BROWN, OF SAME PLACE.

CHIMNEY TOP AND VENTILATOR.

SPECIFICATION forming part of Letters Patent No. 267,805, dated November 21, 1882.

Application filed July 14, 1882. (No model.)

To all whom it may concern:

Be it known that I, EMIL R. STASCH, a citizen of the United States of America, residing at Corning, in the county of Steuben and State 5 of New York, have invented certain new and useful Improvements in Chimney Tops and Ventilators, of which the following is a specification, reference being had therein to the accompanying drawings.

10 This invention relates to an improvement in chimney-top caps or ventilators, having for its object to remedy the smoking of chimneys; and it consists of a pipe with a hood or deflector connected to its upper end in a manner to prevent downward currents of air reaching or passing into it, and at the same time adapted to permit the smoke to pass out, substantially as hereinafter more fully set forth.

In the accompanying drawings, Figure 1 is 20 a side view of my improved chimney cap or cowl, and Fig. 2 is a sectional elevation of the same.

A is the pipe, which is fastened to the top of the chimney. To the upper end of this pipe, around its opening, is affixed a downwardly-inclined annular flange, *a*, while above this end of the pipe is arranged a similarly-inclined cone, *b*, connected to and supported upon the upper ends of bars, *b'*. These bars are fastened upon the deflector or flange *a*. Inclosing or covering the cone and flange is a second cone, or rather truncated cone, *B*, open at its under side and top arranged intact therewith and supported upon and fastened to the lower ends of the bars *b'*. This arrangement, it will be observed, permits the smoke to readily escape, it passing from the pipe between the deflectors and out between them or up through the deflector or hood *B*, while downward cur-

rents of air are prevented from entering the 40 pipe and driving the smoke back down the chimney-flue, thus overcoming the tendency to smoke from that source. In Figs. 3 and 4 the pipe is connected to a cross-head pipe, *C*, through which the smoke first passes, and then 45 through apertures *c* in the inner cone, *b*, the deflector or flange *a* being omitted and said cone caused to take its place. The pipe *C* takes the place of the flange *a*, as above intimated.

I am aware that chimney-cowls have been constructed and patented with a pipe having a downwardly-projecting flange, a cone suspended above it, and the whole surrounded by a deflector contracted at both ends and enlarged at the middle, the outside deflector attached by straps at its lower end to the pipe, the inner cone or deflector attached by straps from its outer upper side to the inner upper side of the large deflector. Therefore this I do 60 not broadly claim; but

What I desire to secure by Letters Patent is—

In combination, the pipe *A*, having its upper end surrounded with a downwardly-projecting flange or deflector, *a*, the hollow deflecting-cone *b*, held above said pipe and flange by bars *b'*, and the truncated-cone-shaped deflector *B*, open at the top and bottom, and held in place by the extended arms *b'*, as shown and described.

In testimony whereof I affix my signature in presence of two witnesses.

EMIL R. STASCH.
